GUSTAVE REHMANN

BY
Fred L. Fraenzel,
ATTORNEY

UNITED STATES PATENT OFFICE.

GUSTAVE REHMANN, OF NEWARK, NEW JERSEY.

INSTRUMENT OR OTHER CASE.

SPECIFICATION forming part of Letters Patent No. 657,708, dated September 11, 1900.

Application filed May 21, 1900. Serial No. 17,337. (No model.)

To all whom it may concern:

Be it known that I, GUSTAVE REHMANN, a citizen of the United States, residing at Newark, in the county of Essex and State of New Jersey, have invented certain new and useful Improvements in Instrument or other Cases; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 My present invention has reference to improvements in pocket or other suitable cases for the placing therein of surgical instruments, but which are also applicable to other uses, such as the carrying therein of cigarettes and other articles.

20 The invention relates more particularly to a novel construction of pocket or other case provided with a supporting plate or plates made of a resilient material removably arranged in the case, said supporting plate or plates preferably being provided with suitable holding means for retaining the surgical instruments or other articles in place upon said plate or plates after being removed from 25 the body of the case.

25 The principal object of this invention therefore is to produce a pocket or other case for the purposes above enumerated which shall be neat in appearance and shall be of a simple, strong, and durable construction, providing a case for more readily presenting the articles therein by quickly removing the supporting plate or plates from the case to facilitate the removal of the articles from the plate 30 for their proper manipulation.

40 My present invention therefore consists in the novel construction of pocket or other case embodying the principles hereinabove mentioned and of the character to be more fully described in the following specification.

45 This invention consists, furthermore, in the several novel arrangements and combinations of the various parts, as well as in the details of the construction thereof, all of which will 50 be hereinafter fully set forth, and then finally embodied in the clauses of the claim appended to this specification.

The invention is fully illustrated in the accompanying drawings, in which—

Figure 1 is a perspective view of a case 55 with which my invention is to be used. Fig. 2 is a plan view of the case with the pocket-sections in open relation to each other, illustrating in plan in one of said sections or in the body of the case a removably-placed supporting-plate for carrying surgical instruments. Fig. 3 is a vertical cross-section taken on line 3 3 in Fig. 2. Fig. 4 is a longitudinal vertical section taken on line 4 4 in said Fig. 2, illustrating in connection therewith the 60 holding arrangement of the resilient supporting-plate for carrying surgical instruments; and Fig. 5 is a similar section illustrating the manner of removing said resilient supporting-plate from the case or the manner of replacing 65 it in said case.

Similar letters of reference are employed in all of the said above-described views to indicate corresponding parts.

Referring to the said drawings, A indicates 75 the complete case, which consists, essentially, of a body *a* and a cover *a'*, provided with the usual forms of perforated ears or lugs *a*², suitably connected by means of a pin, whereby the sections *a* and *a'* are pivotally connected and can be closed down upon each other, as will be clearly evident. The body or section *a*, as will be seen from the several figures of the drawings, is provided on the front with a lug or pin *b*, having a head *b'*. 80 Suitably secured to the front face *a*³ of the cover or section *a'*, by means of a pin or pins *c*', is a sliding catch *c*. The construction of this catch is more particularly represented in Fig. 1. The said catch *c* consists, essentially, of a plate-like body having a pair of downwardly-extending portions *c*² and *c*³, one of which, as *c*³, having a stud-like projection *c*⁴, which extends toward the portion *c*². In this manner a vertical opening or slot *c*⁵ is 85 formed, which communicates with a laterally-extending slot or opening *c*⁶, substantially as illustrated. When the two sections *a* and *a'* of the case A are to be closed, the catch *c* is passed over the pin or stud *b* and causing 90 the head *b'* of the latter to engage with the edges of the parts which surround said slot or opening *c*⁶, whereby the catch *c* will cause 95 the holding or locked engagement of the 100

cover-section a' with the body a of the case A, as will be clearly understood.

As clearly indicated in Figs. 2 to 5, inclusive, suitably secured to the inner surfaces 5 of the sides a^7 and a^8 of the body-section a of the case A, near the upper edges of said sides and preferably extending above said edges to provide a ledge around which the cover-section a' fits when closed, is a strip or 10 band f . Said strip or band f extends part way down the inner surfaces of the sides of said body-section a toward the bottom of the case A, thereby forming a surrounding shoulder f' , substantially as illustrated. Loosely 15 and removably arranged within said body-section a is a supporting-plate e of any desirable configuration, said plate being provided with any number of suitably-placed clamping or holding lugs or ears, as e' , between which can be held a syringe and other surgical instruments, or said plate e may be provided with any other desirable means for holding cigarettes or other articles of manufacture in position thereon. The said plate 25 e is resilient, being preferably stamped or struck up from spring metal, and it is removably held in place beneath the shoulder f' of the surrounding band or strip f by means of the edge e^3 on an upwardly-extending portion e^2 at one end of the plate e and a shoulder e^5 , connected with an upwardly-extending portion e^4 at the opposite end of said plate e , substantially as illustrated in said 30 Figs. 2, 3, and 4. The said portion e^4 is also preferably provided above the shoulder e^5 with a suitably-shaped finger-piece e^6 , by means of which when a direct pressure is applied against said finger-piece, as indicated in Fig. 5, the plate e can be sufficiently bent 35 to permit of its removal from holding engagement with the shoulder f' of the band or strip f to remove the plate e from the section a of the case A or for forcing it into its holding position in the body of said case, as will be clearly understood.

From the above description it will be seen that a neat and simply-constructed case provided with a removable supporting-plate for surgical instruments or other articles of manufacture is the result, which can be conveniently carried in the pocket and from which the plate e , with the instruments thereon, can be readily removed for the more convenient handling of the instruments.

From an inspection of the drawings it will be evident that by slight changes in the outline or configuration of the plates e one or more of such plates can be removably held in place beneath the shoulder f' of the band 55 or strip f , the plates e being of sufficient resiliency that they can be easily forced in position in the case A and can be just as quickly removed therefrom when required.

Of course I am aware that changes may be 60 made in the several arrangements and combinations of the various parts, as well as in the details of the construction thereof, with-

out departing from the scope of my present invention. Hence I do not limit my invention to the exact arrangements and combinations of the parts as herein shown and described, nor do I confine myself to the exact details of the construction thereof.

Having thus described my invention, what I claim is—

1. As a new article of manufacture, a case, consisting of a pair of hinged sections, and a ledge or projection on one of said sections, extending above the surrounding upper and free edge of said section to provide a receiving-flange for the other section, a resilient supporting-plate in said section having said ledge, and holding portions on said plate adapted to be sprung under said ledge and hold said plate in detachable engagement with said section, substantially as and for the purposes set forth.

2. As a new article of manufacture, a case, consisting of a pair of hinged sections, and a ledge or projection on one of said sections, 90 extending above the surrounding upper and free edge of said section to provide a receiving-flange for the other section, a resilient supporting-plate in said section having said ledge, an upwardly-extending holding portion at one end of said supporting-plate, and an upwardly-extending holding portion at the other end of said plate, adapted to be brought in spring-like holding engagement with the under shoulder of said ledge, substantially 95 as and for the purposes set forth.

3. As a new article of manufacture, a case, consisting of a pair of hinged sections a and a' , a band or strip f in said section a forming a shoulder f' , a supporting-plate e in said section a , an upwardly-extending holding portion e^2 at one end of said plate e , and an upwardly-extending holding portion e^4 at the other end of said plate e , said holding portions being adapted to be brought in spring-like holding engagement with the shoulder of said strip or band f , substantially as and for the purposes set forth.

4. As a new article of manufacture, a case, consisting of a pair of hinged sections a and a' , a band or strip f in said section a forming a shoulder f' , a supporting-plate e in said section a , an upwardly-extending holding portion e^2 at one end of said plate e , and an upwardly-extending holding portion e^4 at the other end of said plate e , said holding portion e^2 having a straight edge e^3 and said holding portion e^4 having a shoulder e^5 , said edge e^3 and said shoulder e^5 being adapted to be brought in spring-like holding engagement 115 with the shoulder of said strip or band f , and a finger-piece e^6 above said shoulder e^5 on said holding portion e^4 , all substantially as and for the purposes set forth.

5. As a new article of manufacture, a case, 130 consisting of a pair of hinged sections, and a ledge or projection on one of said sections, to provide a shoulder at or near the upper and free edge of said section, a supporting-plate

in said section, an upwardly-extending holding portion e^2 at one end of said plate, and an upwardly-extending holding portion e^4 at the other end of said plate, adapted to be brought in spring-like holding engagement with the shoulder formed by said ledge, substantially as and for the purposes set forth. 5

6. As a new article of manufacture, a case, consisting of a pair of hinged sections, and a ledge or projection on one of said sections, to provide a shoulder at or near the upper and free edge of said section, a supporting-plate in said section, an upwardly-extending holding portion e^2 at one end of said plate, an up-

wardly-extending holding portion e^4 at the other end of said plate, adapted to be brought in spring-like holding engagement with the shoulder formed by said ledge, and a finger-piece connected with said holding portion e^4 , substantially as and for the purposes set forth. 15 20

In testimony that I claim the invention set forth above I have hereunto set my hand this 17th day of May, 1900.

GUSTAVE REHMANN.
